UNITED STATES PATENT OFFICE.

THOMAS BRADEN, OF DES MOINES, IOWA.

ALARM ATTACHMENT FOR DOOR-KNOBS.

SPECIFICATION forming part of Letters Patent No. 445,218, dated January 27, 1891.

Application filed May 29, 1890. Serial No. 353,526. (No model.)

To all whom it may concern:

Be it known that I, THOMAS BRADEN, a citizen of the United States, residing at Des Moines, in the county of Polk and State of Iowa, have invented a new and useful Improvement in Alarm Attachments for Door-Knobs, &c., of which the following is a specification.

My invention consists in the construction and combination of a detent or stop, a device adapted to clasp a door-knob, and alarm mechanism with a case or frame in such a manner that the frame and the bell and operative mechanism carried thereby will serve as a pendulum, as hereinafter set forth, pointed out in my claims, and illustrated in the accompanying drawings, in which—

Figure 1 is a front elevation of my improved door-knob alarm, the cover, plate, and bell being removed to show the parts. Fig. 2 is a side view of the same, the bell being in section. Fig. 3 is a top sectional view on line x x, Fig. 1, the bell being broken away.

A represents the frame of my attachment, which is formed with an upwardly-projecting portion a.

B B are slotted spring-embracing arms, which, as shown, are secured to a pivoted portion b, with which the depending stop C is integrally formed. I do not desire, however, to be understood as limiting myself to the structural form of suspension shown, since the embracing-arms may be continued and formed into a loop about the knob; or I may employ wire to accomplish the same result. It will be observed that the portion b is pivoted at b' to the projecting portion a of the frame A.

Referring now to the mechanism for operating the bell-hammer, D D² is a convolute spring of ordinary form, one end of which is secured to the shaft d, journaled within the frame, the outer end of said shaft being screw-threaded, with which the threads of a corresponding shaft d', secured to the gong E, mesh, so that the spring may be wound up by the gong.

H is a toothed wheel fixed on the shaft d, and h is a ratchet-wheel, also fixed to said shaft, with which a pawl h' engages, being held in engagement in one direction of revolution by the spring h'', thus holding the

spring D² from unwinding. The wheel h engages a pinion J on the shaft j, journaled in the frame of the toothed wheel K, which latter is thus actuated by the spring when the alarm is to be sounded, being engaged by the pawls k k', formed with the rock-shaft L, also journaled within the frame. The bell-hammer D is also fixed to the said rock-shaft L, which latter has a tang M in such a position and extending in such a direction as to be engaged by the stop C when the suspending device is in a vertical plane.

The operation of my device is as follows: The attachment may be secured upon a door-knob by means of the arms B B, which are sprung about the periphery of the knob. In the normal position of the parts the suspending device and the actuating mechanism and bell are in the same plane, the stop C engaging and holding the tang M, which in turn confines the rock-shaft L, the pawls k and k' of which engage the toothed wheel K and hold the same from rotation against the action of the spring D², the tendency of which latter is constantly to rotate the said wheel K. By this means the bell-hammer D remains inactive. Whenever the door-knob is turned in either direction, the frame and the mechanism therein and the bell being pivotally connected to the suspending device remain in the same vertical plane as before, while the lower end of the stop C is turned to describe an arc, which relieves the tang M and the rock-shaft L, the pawls k and k' being also released from their engagement of the wheel K. The spring D² rotates the said wheel, which, by means of the pawls k and k', imparts an intermittent movement to the bell-hammer D, sounding the alarm. When the door-knob springs back again into its normal position, the stop C again engages the tang M and causes the alarm to cease sounding.

Having thus described my invention, what I claim as new, and desire to secure by Letters of the United States, is—

1. In an alarm attachment for door-knobs, a case or frame adapted to support and carry a bell and striker and operative mechanism having an upward projection at its top and center, a detent or stop pivoted to the top of said frame, and a knob-clasping device fixed to said detent or stop, arranged and combined

to operate in the manner set forth, for the purposes stated. 2. An improved alarm attachment for door-knobs, consisting of a frame or case having a 5 detent or stop pivoted to its top portion and a knob-clasping device fixed to said detent or stop, a bell and striker, and mechanism for operating the striker, attached to and carried by said case or frame, and combined with said 10 detent or stop, to operate in the manner set forth, for the purposes stated.

3. The frame A, having an integral projection *a*, the stop C, pivoted to said projection, the spring-arms B, fixed to said stop, the shafts

d and *d'*, and the gong or bell E, the spring 15 *D*, the toothed wheel *H*, fixed to the shaft *d*, the ratchet-wheel *h*, fixed to the shaft *d'*, the shaft *j*, having a fixed pinion or lantern wheel *J*, the rock-shaft *I*, carrying the hammer *D*, pawls *k* and *k'*, and a tang or extension *M*, 20 arranged and combined substantially as shown and described, for the purposes specified.

THOMAS BRADEN.
